UNITED STATES PATENT OFFICE.

MELVILLE CLARK, OF CHICAGO, ILLINOIS.

PERFORATED NOTE-SHEET FOR AUTOMATIC MUSIC-PLAYING INSTRUMENTS.

No. 889,905.

Specification of Letters Patent.

Patented June 9, 1908.

Application filed June 7, 1907. Serial No. 377,694.

To all whom it may concern:

Be it known that I, MELVILLE CLARK, a citizen of the United States, residing at Chicago, in the county of Cook and State of Illinois, have invented new and useful Improvements in Perforated Note-Sheets for Automatic Music-Playing Instruments, of which the following is a specification, reference being had to the accompanying drawings, forming a part thereof.

This invention is designed to provide an improved construction of perforated note sheet for accenting or emphasizing any desired notes, as, for example, the notes constituting the melody of a piece of music played by an automatic music-playing instrument especially adapted for that purpose when the melody notes are played by the same automatic action as the rest of the music.

It consists of the features of construction which are shown and described as indicated in the claims.

In the drawings:—Figure 1 is a front elevation showing a portion of a perforated note sheet embodying this invention located in operative conjunction with a tracker board of an automatic music-playing instrument, the note-sheet being broken away to uncover the mouth edge of the tracker board. Fig. 2 is a similar view presenting a modification in which the tracker board has an exceptional form of duct mouth to accomplish the purpose of the invention. Fig. 3 is a view similar to the preceding figures in which the perforated sheet and the tracker board have respectively special form of aperture and special form of duct-mouth coöperating to effect the purpose of the invention. Fig. 4 is a detail section at the line 4—4 on Fig. 3. Fig. 5 is a detail section at the line 5—5 on Fig. 2.

It is understood in the art of auto-pneumatic music-playing instruments that special devices may be provided and automatically controlled for causing the striking devices to operate more or less forcibly upon the sounding devices of the instrument played, and that for selecting particular notes to be thus exceptionally sounded there may be provided certain supplemental apertures in the note sheet for controlling the stroke-modifying devices, the apertures for the notes to be affected being cut out of line with the remaining apertures of their respective chords so as to reach the corresponding tracker duct

mouths at the time the striking devices are under the control of the stroke-modifying devices, so that these particular notes, and these only whose apertures are thus cut out of line with the remainder, shall experience the effect of the tone-modifying devices. In Fig. 1 of the drawings, for example, there are shown in the perforated note sheet, A, apertures, a , a , for playing the accompaniment notes and apertures, a^1 , for playing the melody notes, one such special aperture, a^1 , being present in each transverse group of apertures corresponding to a chord of the music. These special apertures, a^1 , are cut in advance of the apertures, a , and in line with a supplemental aperture a^2 , which is designed to coöperate with a corresponding supplemental tracker duct for controlling the stroke-modifying devices, whatever they may be and without regard to their specific character. When the apertures, a^2 and a^1 , reach their respective tracker mouths, the stroke-modifying devices being operated or adjusted by the pneumatic action which is influenced through the aperture, a^2 , the stroke which is produced by the automatic action which is influenced by the aperture, a^1 , will be exceptional; and this stroke having been made,—promptly thereafter,—and so shortly after that the interval will not be unpleasantly perceptible, the remaining apertures, a , of the chord reach their respective tracker duct mouths and cause the accompaniment notes to be sounded without the exceptional character.

With certain forms of construction the tone-modifying device is of such character that it must be caused to operate after the notes of the accompaniment have been struck so that they shall not be affected by it, and in such case the marginal perforation of the note sheet and the specialized aperture for the melody note will be cut back of their normal alinement with other apertures in order to specialize the melody note. Such construction is illustrated in Fig. 2. In either case, unless special provision to the contrary is made, when the tracker board is made adjustable transversely with respect to the note sheet or the note sheet made adjustable width-wise with respect to the tracker board for transposing the key in which the music is played, such adjustment would carry the mouth of the tracker duct which coöperates with the marginal aperture, a^2 , of the tracker sheet out of the path of that aperture, and

the specializing of the melody notes would be possible only at one point within the range of transposition thus provided for. To overcome this defect and make the expedient for 5 specializing or emphasizing the melody operative throughout the entire range of transposition provided for by the relative adjustments of which the tracker board and note sheet are made susceptible, I make the marginal aperture, a^2 , of the note sheet elongated transversely of the path of travel of the sheet, such elongation being sufficient to cover the whole or any desired portion of the range of 10 transposition. An obvious modification or supplement of this expedient consists in expanding longitudinally with respect to the tracker board,—that is, transversely with respect to the path of the note sheet,—the mouth of the tracker duct which coöperates 15 with the marginal aperture, a^2 , of the note sheet. The two expedients may be combined, a part of the range of transposition being provided for by elongating the aperture and the remainder by expanding the tracker 20 duct mouth. In Fig. 3 I have shown both expedients and this figure may be taken as indicating a provision for a portion of the transposition in each of the two coöperating elements—tracker board and note sheet— 25 but it will be understood also without further specific illustration that either element may be made to provide for the full range of transposition, the other element in that case being left of normal dimensions.

35 I claim:

1. In an automatic music-playing instrument, in combination with a tracker board having a supplemental duct; a perforated note sheet having apertures for the notes to be emphasized cut out of normal tracker alinement at their leading ends with the notes which are not to be emphasized, and a supplemental aperture for coöperation with such supplemental tracker duct, also correspondingly cut out of normal tracker alinement with the apertures for the unemphasized notes, said supplemental aperture of 40

the note sheet having its dimension transverse of the path of the movement of the note sheet greater than the distance from 50 center to center of the note-controlling tracker-duct mouths.

2. In an automatic music-playing instrument, in combination with a tracker board having a supplemental duct; a perforated note sheet having apertures for the notes to be emphasized cut out of normal tracker alinement at their leading ends with the notes which are not to be emphasized, and a supplemental aperture for coöperation with such supplemental tracker duct, also correspondingly cut out of normal tracker alinement with the apertures for the unemphasized notes, the mouth of said supplemental tracker duct having its dimensions transverse 60 to the path of movement of the note sheet greater than the distance from center to center of the note-controlling duct-mouths of the tracker-board.

3. In an automatic music-playing instrument, in combination with a tracker board having a supplemental duct; a perforated note sheet having apertures for the notes to be emphasized cut out of normal tracker alinement at their leading ends with the 70 notes which are not to be emphasized, and a supplemental aperture for coöperation with such supplemental tracker duct, also correspondingly cut out of normal tracker alinement with the apertures for the unemphasized notes, such supplemental note-sheet aperture and the mouth of the supplemental tracker duct having their respective dimensions transverse to the path of movement of the note sheet greater than the distance from 75 center to center of the note-controlling tracker duct mouths.

In testimony whereof, I have hereunto set my hand at Chicago, Illinois, this 18th day of May, 1907.

MELVILLE CLARK.
